US0D1024090S

(12) **United States Design Patent** (10) **Patent No.:** **US D1,024,090 S**
(45) **Date of Patent:** **** Apr. 23, 2024**

(54) **DISPLAY SCREEN OR PORTION THEREOF
WITH GRAPHICAL USER INTERFACE
ASSOCIATED WITH INSULIN DELIVERY**

(71) Applicant: **Bigfoot Biomedical, Inc.**, Milpitas, CA (US)

(72) Inventor: **Jacob Bowland**, Milpitas, CA (US)

(**) Term: **15 Years**

(21) Appl. No.: **29/788,412**

(22) Filed: **May 19, 2021**

Related U.S. Application Data

(62) Division of application No. 29/676,277, filed on Jan. 9, 2019, now Pat. No. Des. 920,343.

(57) CLAIM

The ornamental design for a display screen or portion thereof with graphical user interface associated with insulin delivery, as shown and described.

DESCRIPTION

The FIGURE is a front view of a display screen or portion thereof with graphical user interface showing the new design.

The broken line showing of a display screen with graphical user interface is included for the purpose of showing portions of the article which form no part of the claim.

1 Claim, 1 Drawing Sheet
